VETERINARY INSTRUMENT

Arthur H. Junge, Reedsville, Wis.

Application April 2, 1935, Serial No. 14,328

1 Claim. (Cl. 128—352)

My invention relates to a veterinary instrument of the obstetrical type for use in connection with cows and mares.

It is well known that a calf or fetus lies on its breast within the uterus, but due to the fact that it rolls on its back, or nearly so, it takes the uterus along with it resulting in the twisting or torsioning of the uterus neck whereby the latter is closed to parturition.

10 It is the aim of my invention to overcome the objection referred to, and to this end, my invention resides in the providing, in a manner as hereinafter set forth, means for removing the twist or torsion in the neck of the uterus, as well as positioning the calf or fetus in a normal anterior presentation or a posterior presentation.

Further objects of my invention are to provide, in a manner as hereinafter set forth, an instrument for the purpose set forth which is simple in 20 its construction and arrangement, strong, durable, compact, thoroughly efficient in its use and comparatively inexpensive to manufacture.

To the above ends essentially and to others which may hereinafter appear, my invention 25 consists of such parts and such combination of parts which fall within the scope of the invention as claimed.

In the drawing:

Figure 1 is a view illustrating the uterus of a 30 cow having a calf arranged therein and further showing the application of the instrument, in accordance with my invention, for removing the twist or torsion in the neck of the uterus and changing the position of the calf, and

35 Figure 2 is a perspective view of the veterinary instrument, in accordance with my invention.

With reference to the drawing, 3, 4, and 5 indicate respectively a cow, its uterus and the neck of the latter. Within the uterus is shown a calf 6 40 lying upon its back.

The instrument, in accordance with my invention, includes an elongated stem 7 of circular cross section and of the desired diameter and length. The inner end of stem 7 merges into a closed loop 45 or eye 8. The outer end of stem 7 merges into a combined diverging and converging head 9 merging into a semi-circular flat protuberance 10 intersected centrally by the longitudinal median of the head. The latter diverges for the greater portion of its length from stem 7 and then converges into the inner ends of the sides of the protuberance 10. The edges and faces respectively of the head and protuberance are rounded and flat. The faces of the protuberance form flush 55 continuations of the faces of the head. The thickness of the head and protuberance is less than the diameter of the stem. The head, in prox-

imity to its point of emergence with the protuberance, is provided with an opening 11. The head 9 is substantially of pear-shaped contour. The side edges of said head are of compound curvature. Carried by the head is a flexible element of the 5 desired length and which, by way of example, is in the form of a chain 13 which extends through opening 11 and is designed for forming an adjustable loop 13a. The chain 13 is provided at one end with a split retaining ring 14 of greater 10 diameter than opening 11 and at its other end with a rectangular endless link 15 having its width greater than the diameter of chain 13.

When using the instrument, the chain 13 is passed through link 15 to form a loop 13a. The 15 chain is then passed through opening 11 and connected to head 9 by ring 14. The veterinarian then places the loop 13a in the uterus and slips it over a leg of the calf or fetus. The veterinarian 20 guides the instrument in the uterus, while an assistant revolves the stem through the medium of a bar 16 extended through loop or eye 8 until the twist or torsion is removed from the neck 5 of the uterus 4. The non-looped portion of chain 13 winds on rod 7 until loop 13a is tight around 25 the leg of the calf or fetus. The stem 7 is turned either clockwise or anti-clockwise, depending upon what direction the twist in neck 5 extends. During the removal of the neck twist or torsion, the calf or fetus is shifted from the position shown 30 in Figure 1 to lie in a normal anterior presentation. It is to be understood that the instrument may be employed in the same manner as on a posterior presentation. It is also to be understood that the instrument may be connected to the nose, 35 head or neck of the calf or fetus.

What I claim is:

In a veterinary instrument; a straight, elongated revolable metallic stem having an integral endless part at its rear end forming a loop for the 40 passage of a revolving means for the stem and an integral flat oppositely flared head part at its other end formed with curved side edges, said head part being provided intermediate its ends with an opening, a metallic chain extending 45 through said opening, a removable metallic ring attached to one end of said chain and coacting with the head part for connecting the head part and chain together, said chain adapted to have a portion thereof wind on said stem, on the revolving of the latter and an enlarged metallic link carried by the other end of said chain for the 50 passage of a stretch of the latter and coacting with said stretch to form an adjustable metallic loop adjacent that portion of the chain wound on 55 said stem.

ARTHUR H. JUNGE.
